US00D732498S

(12) **United States Design Patent**
Huang et al.

(10) **Patent No.:** **US D732,498 S**
(45) **Date of Patent:** **** Jun. 23, 2015**

(54) **PORTABLE ELECTRONIC DEVICE**(71) Applicant: **HTC Corporation**, Taoyuan, Taoyuan County (TW)(72) Inventors: **Chien-Hsin Huang**, Taoyuan (TW); **Hsiao-Chuan Huang**, Taoyuan (TW); **Chih-Ling Chien**, Taoyuan (TW)(73) Assignee: **HTC CORPORATION**, Taoyuan (TW)(***) Term: **14 Years**(21) Appl. No.: **29/454,474**(22) Filed: **May 10, 2013****Related U.S. Application Data**

(63) Continuation-in-part of application No. 29/443,348, filed on Jan. 16, 2013.

(51) **LOC (10) Cl.** **14-03**(52) **U.S. Cl.**USPC ..... **D14/138 G**(58) **Field of Classification Search**

USPC ..... D14/138 R, 341, 346, 345, 138 G, D14/138 AD, 496, 203.1, 203.3, 203.4, D14/203.7, 248, 218, 203.5, 203.6; 455/575.1, 556.1, 556.2, 575.3, 575.4; D21/517, 329; 379/433.01, 433.04; D13/168, 65, 78; 361/679.3, 679.56

CPC H04M 1/02; H04M 1/0202-1/035; G06F 1/1626; H01H 13/85
